[57] CLAIM

The ornamental design for a customer activated terminal enclosure, as shown and described.

DESCRIPTION

FIG. 1 is a front elevational view of a customer activated terminal enclosure showing our new design;

FIG. 2 is a side elevational view thereof, the opposite side being identical;

FIG. 3 is a front elevational view of a second embodiment of our design; and

FIG. 4 is a front perspective view of the customer activated terminal enclosure of FIG. 1 on an enlarged scale. Each side of the second embodiment of our design is identical to that shown in FIG. 2. The rear, top and bottom of both embodiments are unornamented.
